ADJUSTABLE SCHOOL DESK AND SEAT

James E. McCall, Pasay City, Rizal, Republic of the Philippines

Application October 15, 1954, Serial No. 462,417

1 Claim. (Cl. 155—4)

This invention relates to desks used in school rooms and the like, and in particular, a desk and seat combination of the collapsible type wherein the parts are folded together to facilitate storing and shipping and in which both the seat and desk are adjustable so that the device is adapted to accommodate children of different sizes.

The purpose of this invention is to provide a collapsible seat and desk, preferably formed of wood or other suitable material, wherein the parts are adapted to be readily taken apart and also readily assembled and wherein the positions of the seat and desk are readily changed.

Various types of wood, and particularly metal, desks have been provided for school use, and although parts of desks of this type are adjustable, it is difficult to combine the adjustable mounting elements with the collapsible construction with the desk having sufficient rigidity for use in a school room. With this thought in mind, this invention contemplates a combination seat and desk in which vertically disposed end portions are snugly fitted in sockets in horizontally disposed elements whereby with the parts secured together with bolts and with the bolts extended through slots the parts are rigidly and at the same time adjustably held.

The object of this invention is, therefore, to provide means for forming a collapsible seat and desk in which the parts are adapted to be adjusted to accommodate children of different sizes and in which the device has sufficient rigidity for school room use.

Another object of the invention is to provide an adjustable collapsible seat and desk combination for school room use in which the parts are secured together with bolts whereby play, due to expansion and contraction of the elements and also due to wear, may readily be taken up.

A further object of the invention is to provide an adjustable collapsible desk and seat combination for school room use in which the device is of a simple and economical construction.

With these and other objects and advantages in view, the invention embodies floor engaging base members with vertically disposed recesses in inner surfaces thereof, vertically disposed end members fitted in the recesses of the base members and adapted to be secured therein with bolts, a seat carried by cleats with horizontally disposed slots therein secured to the end members with bolts extended through said slots, a desk having upper and lower panels mounted on end walls and an intermediate partition positioned on upper ends of vertically disposed end members at the back of the device and having recesses sufficient to receive the upper ends of said end members, bolts for securing the end walls of the desk to said end members, said bolts being extended through the end walls and vertically disposed slots of the vertically positioned end members, a horizontally disposed panel providing a back for the seat secured to the forward ends of the end walls and partition of the desk, and a foot rest extended between and carried by the said base members.

2

Other features and advantages of the invention will appear from the following description, taken in connection with the drawing, wherein:

5 Figure 1 is an end elevational view of the adjustable collapsible seat and desk combination showing the seat and desk in adjusted positions in broken lines.

10 Figure 2 is a front elevational view of the seat with parts broken away showing the connection of one of the cleats of the seat to one of the vertically disposed end members.

Figure 3 is a rear elevational view of the device with parts broken away showing a connection between one of the end walls of the desk and the upper end of the vertically disposed end member.

15 Figure 4 is a sectional plan taken on line 4—4 of Figure 1 showing the upper portions of the vertically disposed end members nested in a recess of the base member and the bolt connecting the cleat at one end of the seat to the vertically disposed members.

20 Figure 5 is a sectional plan illustrating the construction at one end of the desk and showing an end wall of the desk secured, by a bolt, to the upper end of the rear end member.

25 Figure 6 is a cross section taken on line 6—6 of Figure 1 showing the connection of the foot rest to the base member at one end of the device and also showing the lower end of one of the vertically disposed end members extended upwardly from said connection.

30 Referring now to the drawing, wherein like reference characters denote corresponding parts, the improved school room desk of this invention includes base rails 10 and 11, forward end panels 12 and 13, rear end panels 14 and 15, seat cleats 16 and 17 for supporting a seat 18, a foot rest 19, a horizontally disposed back panel 20, and a desk having a top or upper panel 21, a lower panel 22, end walls 23 and 24, and an intermediate partition 25.

35 The base rails 10 and 11 are provided with intermediate recesses, as indicated by the numeral 26 in Figure 1, wherein end portions forming feet 27 and 28 are provided at the ends to facilitate positioning the desks upon uneven surfaces, and the inner faces of the base rails 10 and 11 are also provided with recesses, as indicated by the numeral 29 in Figure 4, with shoulders 30 and 31 at the ends whereby with the lower ends of the panels 12 and 14 at one end and 13 and 15 at the opposite end snugly fitted and nested in the recesses the vertically disposed end panels are adapted to be wedged and rigidly held. The lower ends of the panels 12 and 13 are clamped to the base rails with bolts 32 and 33 and the lower ends of the panels 14 and 15 with bolts 34 and 35.

40 The foot rest 19 which is provided with a beveled upper surface 36 is supported by tongues 37 which, as illustrated in Figure 2, extend below the lower ends of the vertically disposed end panels and also into the recesses 26 of the base rails, and these tongues are secured to the base rails with bolts 38 which are adapted to be selectively positioned in spaced openings 39. By this means the foot rest is adjustable forwardly and rearwardly by moving the foot rest 19 into a comfortable position for the occupant and inserting the bolts 38 in the openings 39 most closely approximating the required position.

45 The cleats 16 and 17 which support the seat 18, are provided with elongated slots 40 through which bolts 41 extend, the bolts being positioned in openings in the panels 12 and 14 at one end and 13 and 15 at the other end, as illustrated in Figure 1. The panels 12 and 13 are provided with additional openings, as indicated by the dotted lines 42, and the panels 14 and 15 have similar openings as indicated by the dotted lines 43 whereby the cleats are adapted to be moved upwardly and outwardly with the bolts 41 extended through the openings

42 and 43 and also through the slot 40. The rear portions of the cleats, beyond the slots 40, are reinforced with screws 44 which extend across the slots and into the upper portions of the cleats. The inner portions of the cleats 16 and 17 are provided with recesses, as indicated by the numeral 45 and as shown in the broken away portion in the intermediate part of Figure 2, and with the seat, as shown in Figure 1, shoulders 46 at the upper ends of the recesses rest upon the upper ends of the forwardly disposed panels 12 and 13.

The upper portions of the vertically disposed panels 14 and 15 are provided with elongated slots 47, in the lower ends of which a panel 48 may be positioned, and bolts, as indicated by the numeral 49 and which are mounted in the end walls 23 and 24 of the desk, extend through the slots, providing means for adjustably mounting the desk in the upper portions of the end panels. The panel 48, which is secured in position by bolts or wood screws, may or may not be used as may be desired. The bolt 49 provides means for adjusting the elevation of the desk, as indicated by the broken lines in Figure 1, and, as illustrated in Figure 5, the end walls 23 and 24 are provided with recesses 51 having shoulders 52 and with the upper ends of the panels 14 and 15 wedged between the shoulders 52 and rear surface of the back panel 20 the desk portion of the assembly is rigidly held.

The back panel 20 is adapted to be secured in position with screws 53, or by other suitable means, and the panels 21 and 22 are secured to the end walls and the intermediate partition with a suitable adhesive or by the use of screws or other fastening elements.

With the parts formed as shown and described, a seat may readily be assembled with the vertically disposed end panels wedged in the recesses 29 of the base rails and with the seat and desk adjustably mounted on the end panels. With the parts bolted together, the seat assembly may readily be separated with the desk and seat removed from the vertically disposed end panels and with the end panels and foot rest removed from the base rails. With the bolts extended through the slots, the parts are readily adjustable and it will be understood that the last seat of a row, or a seat adapted to be positioned with the back against the wall, may be assembled with the desk omitted and with the rear portion of the base rails formed to provide feet. With the device used as a back or last seat of a row, the extended portions of the seat or the base rails may be omitted whereby a straight surface may be provided at the back or rear edges of the vertically disposed end panels 14 and 15.

The intermediate partition 25 may or may not be used as may be desired, and whereas this is particularly desirable to provide separate book retaining compartments in a double desk, it is not necessary in a single desk.

This desk is designed particularly to answer the school desk problem in the backward countries of Middle East

and South East Asia where there is a need for desks and seats light in weight and at the same time durable, and wherein the desks can be constructed in the local shops and with unskilled labor and with local and inexpensive materials. For the same reasons the desks are collapsible, portable, and must conform to hygienic requirements.

It will be understood that other modifications, within the scope of the appended claim, may be made in the design and arrangement of the parts without departing from the spirit of the invention.

What is claimed is:

In a desk and seat combination for use in a school room, the combination which comprises spaced parallel base rails with recesses in lower edges thereof providing feet at the ends and with vertically disposed recesses in inner faces thereof, forward and rear panels positioned with lower ends thereof wedged in the recesses of the base rails and with upper parts extended upwardly from said base rails, bolts extended through the lower ends of the panels and base rails for securing the panels to the base rails, a foot rest having an inclined upper surface extended between said base rails and adjustably mounted on said base rails, bolts extended through upper portions of the forward and rear panels, said forward and rear panels having a plurality of bolt holes therein, a seat having vertically disposed cleats on the lower surface positioned with the cleats against outer surfaces of the end panels, said cleats having elongated horizontally disposed slots extended inwardly from rear ends thereof and said slots being positioned to receive bolts extended through the bolt holes of the end panels, providing adjustment of the seat forwardly, rearwardly, upwardly and downwardly, the rear end panels having elongated vertically disposed slots extended downwardly from upper ends thereof, a desk having horizontally disposed upper and lower panels connected with end walls and an intermediate partition and having a back panel on the forward end, said end walls of the desk having vertically disposed recesses in outer surfaces thereof and said recesses being adapted to receive upper ends of said rear panels, and bolts positioned in the end walls of the desk and adapted to be positioned in the slots of said rear panels for adjustably securing the desk to said end panels, the upper ends of said end panels at the rear of the device being adapted to be wedged in the recesses of the end walls of the desk and between shoulders of the end walls and extended ends of said back panels.
